UNITED STATES PATENT OFFICE.

JOSEPH BERG, OF CHICAGO, ILLINOIS, ASSIGNOR TO STEWART-WARNER SPEEDOMETER CORPORATION, OF CHICAGO, ILLINOIS, A CORPORATION OF VIRGINIA.

INSTRUMENT-BOARD FOR AUTOMOBILES.

1,273,448.

Specification of Letters Patent. Patented July 23, 1918.

Application filed January 27, 1917. Serial No. 144,837.

To all whom it may concern:

Be it known that I, JOSEPH BERG, a citizen of the United States, residing at Chicago, in the county of Cook and State of Illinois, have invented new and useful Improvements in Instrument-Boards for Automobiles, of which the following is a specification, reference being had to the accompanying drawings, forming a part thereof.

10 The purpose of this device is to provide convenient means of mounting instruments, such as speedometers, oil gages or time pieces on automobiles, in a desirable and accessible location; the board itself is so 15 constructed as to be attachable without demounting or marring the vehicle to which it is applied. It consists in the elements and features of construction shown and described as indicated in the claims.

20 In the drawings:

Figure 1 is a transverse vertical section of a portion of an automobile equipped with this device.

25 Fig. 2 is a view on an enlarged scale of one end of the board.

Fig. 3 is a cross-section of the board on line, 3—3, of Fig. 1.

30 Fig. 4 is a section on the line, 4—4, of Fig. 1.

The drawings show conventionally the lower portion of a wind shield having the side rails, 1—1, and the bottom rail, 2, supported on the sides, 3—3, of the car body and the front member or cowl, 4, by means 35 of the fittings or brackets, 5—5, the brackets being secured thereto by the bolts, 6—6 and 7—7. The member, 8, is snugly fitted to the flange, 4^a, and arranged to seal the joint between the members, 4 and 2, all in 40 the usual manner.

The instrument board, 10, is mounted immediately under the wind-shield and preferably flush with the associated element, 8; to attain such relation, the board, 10, has, 45 along its upper edge a double angle bend so arranged that when the corner, 11, is brought to bear against the inside of the member, 8, the visible sides of both parts, 8 and 10, may be made flush by either opening or closing the corner, 12, as the case may 50 require, thereby forcing the member, 10,

forward or backward to fit as desired. A flange, 13, of considerable width is arranged substantially in a horizontal plane to stiffen the upper portion of said member, 10, and to resist any tendency of deflection from its vertical plane. Between the bends at 55 12 and 14, the metal takes a downward slope to more readily shed any condensation of moisture. To stiffen the bottom of the member, 10, there is provided a flange, 15.

To secure the device in position the nuts, 6^a, 6^b and 7^a, 7^b, are removed, the bolts, 6, 6, are partly withdrawn and the ears, 16, 16, 17, 17, which project below and above, near 60 the ends of the board, are slipped over the bolts, 6—6 and 7, 7, whereupon the nuts are replaced and tightened. It will be noticed that brackets, 5—5, for which the bolts just mentioned are provided have not been disturbed, thus making the installation of the 65 device a very simple operation.

For mounting any of the accessories commonly used in a motor car, holes may be cut in wherever required, as for instance the 70 opening, 20, which permits the instrument to be set "flush" and allows of any connections being easily made thereto as in the case of a speedometer or odometer, the train resetting device of which may be conveniently reached whether it be located on the far side of the board, or arranged to project 75 through the opening at 20^a.

I claim:

1. In an instrument board of the character described, adapted to extend from side to side of the vehicle body, adjacent to the cowl and wind-shield, lugs or ears projecting from the top near the ends, said lugs or ears being back of the plane of the board, 80 and lugs or ears depending from the board near the ends disposed in planes transverse to that of the aforesaid lugs or ears, each of said ears constituting the means of securing the device in position.

2. In an instrument board of the character described, having perforated lugs adapted for securing to a vehicle body, adjacent to the wind shield, a double reentering-angle bend along the top thereof adapted 100 to engage an associated member, said reentering-angle bend constituting means for

adjusting the said board in the manner and for the purpose set forth and described.

3. In an instrument board of the character described adapted to be secured in position across the vehicle body, adjacent to the wind shield, a ledge or bend along the top thereof, said ledge being bent at an ob-

tuse angle to the board, for the purpose set forth and described.

In testimony whereof, I have hereunto set my hand at Chicago, this 18 day of January, 1917.

JOSEPH BERG.
